his atty.

UNITED STATES PATENT OFFICE.

WILLIAM C. WATKINS, OF WESTON, OHIO.

DAVENPORT-CASKET.

1,321,579.

Specification of Letters Patent.

Patented Nov. 11, 1919.

Application filed October 26, 1918. Serial No. 259,762.

To all whom it may concern:

Be it known that I, WILLIAM C. WATKINS, a citizen of the United States, and a resident of Weston, in the county of Wood

5 and State of Ohio, have invented a certain new and useful Davenport-Casket; and I do hereby declare the following to be a full, clear, and exact description of the invention, such as will enable others skilled in the art 10 to which it appertains to make and use the same, reference being had to the accompanying drawings, and to the characters of reference marked thereon, which form a part of this specification.

15 This invention relates to caskets, and has for its object the provision of a casket which is adapted to be set up in the form of a davenport for display purposes or to be compactly folded in the form of a casket.

20 A further object of the invention is the provision of improved means within the casket for adjusting the position of the shoulders of a body disposed therein.

A further object of the invention is the 25 provision of an improved adjustable top for the casket, which may be opened to any desired extent without disturbing the flowers or other articles which may be placed on the top of the casket.

30 The invention is fully described in the following specification, and while, in its broader aspect, it is capable of embodiment in numerous forms, a preferred embodiment thereof is illustrated in the accompanying drawings, in which—

Figure 1 is a perspective view of a casket embodying my invention set up in davenport form. Fig. 2 is a vertical cross-section thereof. Fig. 3 is an enlarged fragmentary 40 view of one end portion of the casket with parts broken away and illustrating the shoulder adjusting means. Fig. 4 is a cross-section of the casket in closed form, and Fig. 5 is a perspective view thereof with the 45 top slide or panel partly open.

Referring to the drawings, 1 designates the bottom, 2, 2 the ends, 3 and 4 the front and rear sides, respectively, and 5 the top of a casket embodying my invention. The 50 ends 2, 2 fixedly rise from the respective end portion of the bottom 1 and the sides 3 and 4 are connected at their inner lower edges to the respective edges of the bottom by hinges 6 so that the sides may be swung 55 outward and downward from the plane of the ends 2 and stand in vertical supporting

relation to the bottom with their hinged ends shouldering thereunder, as shown in Figs. 1 and 2, thus forming supporting members for the casket.

When the sides 3, 4 are in raised or closed position, the top 5 rests on the top edges of the ends and sides, as shown in Fig. 4, and is movably connected to each end by a link 7, which link is pivoted at one end to 60 the top and at its other end to the respective end 2 of the casket in a manner to permit the top to be swung rearward and downward in upright position at the rear side of the casket with its lower edge adjacent to 65 the lower rear edge of the casket and with its upper edge extending a distance above the ends 2, as shown in Figs. 1 and 2. The top cannot be swung to open position, however, until the rear side 4 has been swung 70 downward to its casket supporting position, as the top when swung to open or upright position takes the closed position of the rear side 4 and rests at its ends against the rear upright edges of the casket ends 2. It is 75 evident that when the sides and top of the casket are in open position the casket assumes the form of a davenport with the sides 80 acting as the supporting legs or members, the ends 2 acting as the arms at the ends of 85 the davenport, and the top 5 acting as the back.

A shallow ledge or rail 8 rises a short distance from the forward edge of the casket bottom 1 immediately within the front side 90 3, when in closed position, and extends from one end 2 to the other. A similar rail or ledge 9 rises from the rear edge of the bottom 1 immediately within the side 4 when in upright position except that its end 95 portions are shown as gradually rising to the height of the respective ends 2 to which they are connected, thus serving as a brace for the ends. A ledge 10 is provided at the inner side of each rail 8, 9 and rising on 100 such ledges are the side rails 11 of what may be termed a cot or spring frame, which frame fits within the casket between the ends 2, 2 and rails 8, 9 and is covered by a canvas or other suitable covering 12. A 105 body may be laid directly on this covering or on a mattress or other covering, which may be placed thereover. The frame 11 and its covering serve as a cot for supporting the body. In order to facilitate an adjustment of the shoulders of a body to any desired position, which is usually accom-

plished by stuffing paper or other articles under the shoulders, each side bar 11 of the frame, at its head portion, is provided with a hinged section 13 adapted to be raised or lowered, and such section is supported in adjusted elevated position by a rod 14, which is pivotally attached at one end and sharpened at its other end to be forced into the wooden bottom 1 of the casket at the 10 desired position of adjustment. The cross piece 15 at the head of the cot frame is hinged at each end to the adjacent section 13 to adapt either section 13 to be raised above the plane of the other, as is apparent 15 by reference to the drawings.

The top 5 is provided with a panel 16 which comprises the major portion of the top and is mortised therein for longitudinal sliding movements, the opening movement 20 thereof being toward the foot of the casket. This panel, on which the floral decorations may be placed, can be opened to expose the whole or only a portion of a body disposed within the casket, or it can be entirely removed from the top without disturbing the floral decorations thereon. It is evident that the casket can be upholstered 25 in any desired manner so that it will have an appearance of a casket when in closed or folded form and will have the appearance 30 of a davenport when in open or unfolded form.

I wish it understood that my invention is not limited to any specific construction or arrangement of the parts, as it is capable 35 of numerous modifications and changes without departing from the spirit of the claims.

Having thus described my invention, what I claim as new and desire to secure by Letters Patent, is,—

1. A davenport casket having front and rear portions mounted for swinging movements to serve as supports for the casket when in davenport form, and having its 40 top connected to the casket ends for movement to upright position at the rear of said ends to take the closed position of the rear side and to serve as the back of the davenport.

2. A casket having its ends and bottom 50 relatively fixed and its front and rear sides hinged at their lower edges to the bottom portions for outward and downward swinging movements relative thereto to place the sides in inverted upright supporting relation to the bottom, said casket also having its top connected to the ends to be placed 55 thereover or to be swung to upright position at the rear of the ends to take the position of the rear side and to extend in davenport back form above the ends.

In testimony whereof I have hereunto signed my name to this specification.

WILLIAM C. WATKINS.
